UNITED STATES PATENT OFFICE.

LEE ALBERT CANNADAY, OF FAIRBURN, GEORGIA.

SUSPENSION APPARATUS FOR ELECTRIC HAIR CLIPPERS.

Application filed October 13, 1921. Serial No. 507,439.

To all whom it may concern:

Be it known that I, LEE ALBERT CANNADAY, a citizen of the United States, and a resident of Fairburn, in the county of Campbell and State of Georgia, have invented certain new and useful Improvements in Suspension Apparatus for Electric Hair Clippers, of which the following is a specification.

10 This invention relates to a suspension apparatus for electric hair clippers or the like.

The object of the invention is to provide an apparatus of the above character 15 adapted to be secured to a ceiling or the like for movably suspending an electric hair clipper or similar appliance, in such a manner that one clipper may serve several workmen or barbers.

20 It is also an object of the invention that the suspension means for the clippers be flexible to permit free use of the same, and also permit adjustable lowering of the clippers any distance desired.

25 It is a further and important object of the invention that the suspension means for the clippers be adapted to be manipulated for automatically raising the clippers to a point where the same will be clear of the 30 workmen therebeneath.

Other objects and objects relating to details of construction, combination and arrangement of parts will hereinafter appear in the detail description to follow.

35 The invention is illustrated by way of example in the accompanying drawings, in which;

Figure 1 is a perspective view of the apparatus when fully assembled and suspended 40 from a ceiling,

Figure 2 is a detail view of the clipper supporting hooks,

Figure 3 is a side elevation of the carriage,

45 Figure 4 is an end elevation of the same,

Figure 5 is a side elevation of the spring motor for supporting cable, the housing therefor being shown in longitudinal section,

50 Figure 6 is an elevation of one end of the control drum of the spring motor,

Figure 7 is a vertical longitudinal sectional view of the control drum,

55 Figure 8 is a side elevation of the spring winding plate,

Figure 9 is an inside elevation of one end of the spring motor housing,

Figure 10 is a view similar to Figure 6, but of the opposite end of the drum.

Referring to the drawings more particularly B indicates a pair of brackets which are secured to a ceiling or the like indicated by the dotted line 10 Figure 1; T a rod or track which supports the carriage C; and which in turn has secured thereto the spring motor M.

The brackets B are preferably L-shaped as shown and which may be secured to the ceiling 10 in any suitable manner. The ends of rod or track T extend through the free ends 70 of the brackets B and each end has threaded thereon a wing nut 11 adapted to permit the rod to be removed and also for holding the rod against longitudinal movement.

The carriage C consists of a channel 75 frame 12, the side flanges of which have formed at each end an extension 13 while the bridge portion is longitudinally recessed as at 14 to provide the legs 15. Between each pair of extensions 13 occurring at corresponding ends of the channel frame member 12 there is journaled a grooved wheel 16 adapted to run upon the rod or track T. Also between each pair of extensions 13 there is secured forward of the associated 80 wheel 16, a thimble member 17 by the means of a bolt 18, each thimble supporting a bumper 19 of rubber or the like.

The spring motor M comprises a drum generally indicated by the reference numeral 20 which has formed in its one end a recess 21 and has its other end hollow as at 22. The hollow end of the cylinder is formed with a cross plate 23 and through the cross plate 23 and solid portion 24 of the drum there extends a shaft 25. Upon the end of the shaft 25 associated with the cross member 23 there is fitted a collar 26 which is formed at its inner end with a radial flange 27. The drum 20 is formed 90 with the retaining flanges 28 and 29, the flange 28 being of the greatest thickness and offset upon its inner edge as at 30, at which point the drum has threaded therein a screw 32 for securing the one end of 95 a cable 33.

In the recess 21 of the drum 20 there is disposed a winding spring 34, the inner end of which is secured to the shaft 25 as at 35 Figure 10. Abutting the end of the drum 110

20 is a circular plate 36 which is formed with a nipple 37 adapted to journal the associated end of the shaft 25. In the nipple 37 there is fitted a plug 38 having a squared 5 end 39 adapted for receiving a key for rotating the plate 36. The plate 36 carries a pin 40 which is adapted to be extended into a loop 41 secured to the outer end of the spring 34.

10 The drum 20 is mounted in a housing comprising a casing 42 which is preferably square in cross-section and which is formed with a longitudinal slot in the lower side thereof, through which the cable 33 may extend. Each end of the casing has fitted thereon a cap 43, and each cap is formed with an outwardly depressed portion 44. In the depressed portion 44 of the cap adjacent the end cross member 23 of the drum 20 there is fitted a bushing 45 which journals the corresponding end of the shaft 25. Through the depression 44 of the other cap extends the nipple 37 of the plate 36 and between the plate 36 and associated cap 44 is interposed a ratchet 46, said ratchet being loosely fitted upon the nipple 37 and held against movement with respect to the shaft 25 by the screws 47. Upon the outer face of the plate 36 there is pivoted a pawl 48 which is pressed by the spring 49 for operatively engaging the ratchet 46 and limiting the plate to rotating in one direction.

Upon the inner face of the housing cap 44 supporting the bushing 45 is pivoted a latch 50, the portion 51 of said latch having its inner edge formed with a notch 52 and its forward edge beveled as at 53. The portion 51 of the latch is also covered with hard rubber or the like. The latch 50 is adapted to cooperate with the pins 52 extending from the adjacent end of the drum for holding the drum against rotation in a manner which will later be described.

Referring to Figures 1 and 2 the cable 33 has its free end extended through one passage of a twin-sleeve 54 then through the swivel member 55 of a snap hook 56, and then extended into the remaining passage of the twin-sleeve for securing the same. The twin-sleeve is also formed at its upper end with a pair of ears 57 between which there is pivoted the shank of a hook 58.

The operation of the present apparatus is as follows: Assuming that the apparatus is suspended from a ceiling as shown in Figure 1, and that the track T extends over several barber chairs. The handle of an electric clipper is flexibly attached to the snap hook 56 and the clipper is hung upon the hook 58. A key is used to wind the spring 34 to such an extent that the drum

20 will rotate for winding the cable 33 so that the clippers suspended by the cable will be clear of the workmen therebeneath. When it is desired to use the clippers the same are grasped by the operator and pulled down to the proper level against the tension of the spring 34. Upon the clippers being brought to the proper level the latch 50 will engage one of the pins 52' and hold the drum against rewinding movement. When the workmen are through with the clippers by pulling down upon the cable 33 and then quickly releasing the same the tension of the spring 34 will carry the pins 52' over the notch 52 and rotate the drum in a reverse direction for rewinding the cable sufficiently to raise the clippers above the heads of the workmen and so retain the same. When another barber wishes to use the clippers he grasps the same and moves the carriage C to proper position and then repeats the operation just described for lowering and raising the clippers.

While I have shown and described the preferred form of my invention, I wish it to be understood that I am well aware that the construction, combination and arrangement of parts may be changed by those skilled in the art without departing from the spirit of my invention as indicated by the appended claims.

I claim:—

1. In an apparatus of the character described, a casing, a shaft rotatably supported therein, a drum supported upon said shaft, a winding spring in one end of the drum having its inner end secured to the shaft, a plate rotatable upon said shaft and having the outer end of said spring secured thereto, means whereby said plate may be rotated for tensioning said spring without rotating said drum, and latch means for retaining the drum against rotation in a direction influenced by the tensioning of said spring.

2. In a device of the character described, a casing, a shaft rotatably mounted therein, a drum carried thereby, a winding spring within the drum and having its inner end secured to said shaft, a plate rotatable upon the shaft and secured to the outer end of said spring, means whereby said plate may be manually rotated in a direction for tensioning said spring, pawl and ratchet means between said plate and casing adapted to hold the plate against rotation in a direction for unwinding said winding spring, and latch means associated with said winding drum to hold the same against rotation under the influence of said spring.

LEE ALBERT CANNADAY.
